METALLIC BASE-BOARD

Anthony George Siebenlist, Milwaukee, Wis., assignor to Milcor Steel Company, Milwaukee, Wis., a corporation of Wisconsin

Application October 31, 1931, Serial No. 572,313

6 Claims. (Cl. 189—85)

This invention relates to a metallic base-board the plaster of the wall interlocks. If desired, for buildings.

One of the objects of the invention is to provide a base-board of pleasing and ornamental 5 appearance; of simple, strong and durable construction; which may be conveniently and economically manufactured; and which may be readily and securely interconnected or interlocked with the flooring and with the wall.

10 Other objects and advantages reside in certain novel features of the construction, arrangement and combination of parts which will be hereinafter more fully described and particularly 15 pointed out in the appended claims, reference being had to the accompanying drawing, forming a part of this specification, and in which:

Figure 1 is a fragmentary perspective view 20 showing a base-board embodying the present invention, and illustrating the manner in which it is interconnected with the flooring and the wall, a portion of the metal lathing of the wall being omitted for the sake of clearness in illustration;

Figure 2 is a view in transverse vertical section 25 taken on line 2—2 of Figure 1; and

Figure 3 is a fragmentary view similar to Figure 2 but on an enlarged scale and illustrating a manner in which the wing of expanded metal is interconnected with the upper flange 30 of the base-board.

Referring to the drawing, the numeral 1 designates the body portion of the base-board. Along its lower edge, the body portion is curved outwardly as at 2 to provide a corner moulding structure and this outwardly curved moulding structure 2 has integral therewith a right angle flange 3, the horizontal section 4 of which interfits between the top flooring 5 and the sub-flooring 6. If a concrete floor is employed, the right angle flange 3 is imbedded in the concrete.

40 The upper edge of the body portion has an inwardly and downwardly inclined flange 7 integral therewith. The flange 7 terminates in a channel 8 which receives and is pressed into secure engagement with the lower end portion of an expanded metal wing 9. Between the angle flange 7 and the wing 9 a pocket 10 is formed. At spaced points along the flange 7, slots 11 are provided. When the base-board is put in place 45 the section 4 of its flange 3 rests on the sub-flooring and is overlapped by the top flooring, the ends of which abut the vertical section of the flange 3. The expanded metal wing 9 is disposed up against the lathing L carried by the 50 usual studding designated at 12 and with which

the wing 9 may be secured to the studding by suitable fasteners such as nails 13.

Before the plaster is applied to the wall, concrete or grout 14 may be forced into the space 60 behind the base-board 1 and between the base-board and the lathing, the grouting being introduced through the slots 11. The plaster is then applied and is not only interlocked with the meshes of the expanded metal wing but also is 65 interlocked with the pocket 10. For convenience in manufacturing the expanded metal wings are preferably made separate and then secured to the flange of the base-board in the manner described. However, if desired, the base-board 70 and expanded metal wing may be made of one piece of metal.

The embodiment of the invention shown in the drawing and described above has been selected for the purpose of illustration and it is to be 75 understood that various changes in the size, shape and arrangement of the parts may be made without departing from the spirit of the invention or the scope of the subjoined claims.

The invention claimed is:

1. A base-board consisting of a body plate of metal having means connected with its lower edge adapted to be interlocked with the floor and having means at its upper edge for connecting an expanded metal wing thereto, which wing is adapted to be inter-engaged with the plaster of the wall. 80

2. A base-board comprising a body plate having an inwardly and downwardly directed flange integral with its upper edge and means on the lower edge of the flange for connecting an expanded metal wing thereto, which wing is adapted to interlock with the plaster of the wall and coacting with said flange to define a plaster receiving pocket. 90

3. A base-board comprising a body plate having an inwardly and downwardly directed flange integral with its upper edge and means on the lower edge of the flange for connecting an expanded metal wing thereto, which wing is adapted to interlock with the plaster of the wall and coacting with said flange to define a plaster receiving pocket, said flange having openings to provide for the introduction of grouting into the space behind the plate when the base-board 100 is in position. 105

4. A base-board comprising a body plate having an inwardly and downwardly inclined flange along its upper edge, said flange terminating in a channel, and an expanded metal wing adapted 110

to interlock with the plaster wall and having its plaster of the wall for securing the upper part of the base-board in position.

5. A base-board comprising a metallic body plate having its lower portion curved outwardly to provide a corner moulding structure, means for connecting the lower portion to the floor and means at the upper edge of the plate for connecting an expanded metal wing thereto, 10 which wing is adapted to interlock with the

6. A base-board comprising a metallic body plate having means for securing its lower portion in position and having means at its upper edge for securing an expanded metal wing thereto, which wing is adapted to be interlocked with the plaster of the wall. 80
